UNITED STATES PATENT OFFICE.

JAMES N. CARTER, OF MCKINNEY, TEXAS.

DESIGN FOR A CLOTHES-SPRING.

SPECIFICATION forming part of Design No. 31,972, dated December 12, 1899.

Application filed October 16, 1899. Serial No. 733,838. Term of patent 14 years.

To all whom it may concern:

Be it known that I, JAMES N. CARTER, of McKinney, in the county of Collin and State of Texas, have invented and produced a new and original Design for a Clothes-Spring, of which the following is a full, clear, and exact description.

Reference is to be had to the accompanying drawings, forming a part of this specification, in which similar characters of reference indicate corresponding parts in all the figures.

Figure 1 is a perspective view of a clothes-spring embodying my new design. Fig. 2 is a side elevation, and Fig. 3 is an edge view.

The design consists in a coiled wire having 15 its terminals in the form of side arms *b*, which project laterally in opposite directions from opposite sides of the coil and terminate in loop-like handle members *a*, which project outwardly approximately parallel with the 20 coil.

I claim—

The design for a clothes-spring herein described and shown.

JAMES N. CARTER.
